[57] **CLAIM**

The ornamental design for a hinge for holding tent supporting rods or the like, as shown and described.

DESCRIPTION

FIG. 1 is a side view of my hinge for holding tent supporting rods or the like showing my new design;

FIG. 2 is an end view thereof;

FIG. 3 is a bottom view thereof;

FIG. 4 is a top view thereof; and

FIG. 5 is a perspective view thereof, the portions of tent supporting rods being shown in broken lines for illustrative purpose only.

FIG. 1

FIG. 2

FIG. 3

FIG. 4

FIG. 5
